(57) **CLAIM**

The ornamental design for a sticker for graduation information with quick response code, as shown and described.

DESCRIPTION

FIG. 1 is a front view of a sticker for graduation information with quick response code, showing my new design.

FIG. 2 is a rear view of the sticker of FIG. 1.

FIG. 3 is a side elevation of the sticker of FIG. 1; and, FIG. 4 is a side view of the sticker of FIG. 1.

The broken lines in the drawings show environment that form no part of the claimed design.

1 Claim, 1 Drawing Sheet
